(57) **CLAIM**

The ornamental design for a blade for air conditioner, as shown and described.

DESCRIPTION

FIG. 1 is a front perspective view of a blade for air conditioner, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion, '8' in FIG. 3;

FIG. 9 is an enlarged view of the encircled portion, '9' in FIG. 3;

FIG. 10 is an enlarged view of the encircled portion, '10' in FIG. 6;

FIG. 11 is an enlarged view of the encircled portion, '11' in FIG. 7;

FIG. 12 is another front perspective view thereof as shown in an air conditioner environment;

FIG. 13 is a perspective view of FIG. 12 showing the blade portion in open position; and,

FIG. 14 is an enlarged view of the encircled portion, '14' in FIG. 1.

The evenly dashed broken lines in FIGS. 12 and 13 depict environmental subject matter that forms no part of the claimed design. The evenly spaced broken lines and the areas within them in FIGS. 1, 3, 5, 6, 7, 10, 11, and 14 depict portions of the blade for air conditioner that form no part of the claimed design. The dot-dot-dash broken lines denote the boundaries of the claim and form no part thereof. The dot-dash broken lines in FIGS. 1, 3, 6, 7, 8, 9, 10, 11, and 14 depict the boundaries of the enlarged views that form no part of the claimed design.
